Primary Examiner — Jennifer L Rempfer*Assistant Examiner* — Sarah A Nguyen(57) **CLAIM**

The ornamental design for a mop bucket, as shown and described.

DESCRIPTION

FIG. 1 is a front, left, top perspective view of a mop bucket showing my new design;

FIG. 2 is a front, right, top perspective view thereof;

FIG. 3 is a front view thereof;

FIG. 4 is a back view thereof;

FIG. 5 is an enlarged left view thereof;

FIG. 6 is an enlarged right view thereof;

FIG. 7 is a top view thereof;

FIG. 8 is a bottom view thereof;

FIG. 9 is an enlarged view of the encircled area 9 of FIG. 1;

FIG. 10 is an enlarged view of the encircled area 10 of FIG.

2;

FIG. 11 is an enlarged view of the encircled area 11 of FIG.

7; and,

FIG. 12 is an enlarged view of the encircled area 12 of FIG.

8.

The broken lines shown on the drawings depict portions of the mop bucket that form no part of the claimed design. The dot-dash lines depict the enlarged view boundaries that do not form part of the claimed design.
